US00D512090S

(12) United States Design Patent (10) Patent No.: US D512,090 S
de Groot (45) Date of Patent: * Nov. 29, 2005

(54) TYPE FONT

(75) Inventor: Lucas Adrianus Wilhelmus de Groot,
Berlin (DE)

(73) Assignee: Microsoft Corporation, Redmond, WA
(US)

() Term: 14 Years

(21) Appl. No.: 29/201,672

(22) Filed: Mar. 19, 2004

(51) LOC (8) Cl. 18-03

(52) U.S. Cl. D18/24

(58) Field of Search D18/25, 27, 30,
D18/32; 101/398, 399; 434/159, 160, 161-165
